UNITED STATES PATENT OFFICE.

RICHARD J. EVANS, OF FRANKLIN, PENNSYLVANIA, ASSIGNOR TO FRANKLIN MFG. CO., OF FRANKLIN, PENNSYLVANIA.

DUST-GUARD.

SPECIFICATION forming part of Letters Patent No. 729,307, dated May 26, 1903.

Application filed January 5, 1903. Serial No. 137,872. (No model.)

To all whom it may concern:

Be it known that I, RICHARD J. EVANS, a citizen of the United States, residing at Franklin, in the county of Venango and State of Pennsylvania, have invented certain new and useful Improvements in Dust-Guards, of which the following is a specification, reference being had therein to the accompanying drawings.

10 This invention relates to an improved guard for preventing the entrance of dust and other foreign substances to the journal-boxes and the journals of railway-car axles and also to the shafts of engines, motors, dynamos, and other machinery.

15 The nature of the improvements will be readily comprehended, reference being had to the following detailed description and to the accompanying drawings, in which—

20 Figure 1 is a perspective view of a dust-guard embodying my invention. Fig. 2 is a front elevation of the guard applied to an axle-journal or a shaft. Fig. 3 is a view similar to Fig. 2, partly in section, with the journal-opening of the guard slightly worn. Fig. 4 is a perspective view of the spring connection for the guard-sections.

25 Referring to the drawings by letter, A denotes the guard, which is formed in two parts or sections a a' , lapped at b b and having the circular opening c for the journal or shaft. The bottom edge of the lower guard-section a and the side edges of both sections are grooved, as at a^2 , and in the top of the 30 upper section a' is a central opening a^3 .

35 The upper and lower guard-sections are connected together by a binding-wire D , which occupies the groove a^2 . The upper portions d d of the wire beyond the upper section are 40 downwardly inclined and terminate in abruptly-bent ends d' d' , which enter the opening a^3 . By reference to Figs. 1 and 3 it will be observed that the side portions d^2 d^2 of the wire extend some distance above the top of the 45 upper guard-section, permitting a range of movement of the latter to compensate for wear.

50 The material of the wire is such as will cause the ends d' d' to press with a spring action against the top of the upper guard, whereby the guard-sections are forced tightly

against the journal or shaft regardless of the extent of wear of the wall of opening c . It will be noticed that the wire is in a single piece. Consequently the cost of production is lessened and there is no liability to disorder.

55 While the guard-sections may be made of any suitable material, I prefer to use a fire-proof substance, such as asbestos. It has never before, so far as I am aware, been proposed to construct a dust-guard wholly of this material, whereas by experiment I have found that aside from the quality of being absolutely fireproof there is no charring or deterioration as the result of a heated journal or shaft. Moreover, the material resists wear, will absorb the lubricant, and will not warp or disintegrate.

60 I claim as my invention—

1. A dust-guard consisting of two slidably-joined sections having a journal or shaft opening and each having a groove in its side edges and the lower section having a groove in its bottom edge, and the upper section having a recess centrally in its top, and a binding-wire 70 connecting the sections and having straight side and bottom portions, seated in the grooves, and integral spring ends each projecting at an angle from an extension of a side portion and engaging the recess in the top of the upper guard-section.

75 2. A dust-guard consisting of two slidably-joined sections of asbestos having a journal or shaft opening and each having a groove in its side edges and the lower section having a groove in its bottom edge, and the upper section having a recess centrally in its top, and a binding-wire connecting the sections and having straight side and bottom portions, seated in the grooves, and integral spring ends each 80 projecting at an angle from an extension of a side portion and terminating in downwardly-bent ends engaging the recess in the top of the upper guard-section.

85 In testimony whereof I affix my signature in presence of two witnesses.

RICHARD J. EVANS.
